UNITED STATES PATENT OFFICE.

FRANK O. HOAGLAND, OF BRIDGEPORT, CONNECTICUT, ASSIGNOR TO THE BILTON MACHINE TOOL COMPANY, OF BRIDGEPORT, CONNECTICUT, A CORPORATION OF CONNECTICUT.

SURFACE-PLATE.

1,383,629.

Specification of Letters Patent. Patented July 5, 1921.

Application filed October 29, 1919. Serial No. 334,196.

To all whom it may concern:

Be it known that I, FRANK O. HOAGLAND, a citizen of the United States, and resident of Bridgeport, in the county of Fairfield and State of Connecticut, have invented 5 certain new and useful Improvements in Surface-Plates, of which the following is a specification.

My invention relates to new and useful 10 improvements in surface plates such as are used for machine shop work where a true operating surface is required.

The object of the invention, briefly speaking, is to provide a surface plate wherein 15 the greatest amount of strength and rigidity may be obtained by the use of a minimum amount of material, to construct the same so that it may be produced cheaper than the old form of surface plate and stronger in 20 proportion to its weight; to provide a novel form of construction wherein the material is shaped and distributed in a manner to prevent the plate from warping or otherwise getting out of shape and so as to insure a 25 perfectly true and rigid operating surface.

With these and other objects in view the invention resides and consists in the construction and novel combination and arrangement of parts hereinafter more fully 30 described, illustrated in the accompanying drawings, and pointed out in the claims hereto appended, it being understood that various changes in the form, proportion, size and minor details of construction within the 35 scope of the claims may be resorted to without departure from the spirit or sacrificing any of the advantages of the invention.

Similar characters of reference denote like or corresponding parts throughout the several figures of the accompanying drawings forming a part of this specification, and upon which,

Figure 1 shows a central vertical longitudinal section of the form of surface plate 45 shown in Fig. 2.

Fig. 2 is a bottom view of the plate shown in Fig. 1.

Fig. 3 is a top plan view of a square plate constructed in accordance with the features 50 of my invention.

Fig. 4 is a side view as seen from either the right or left of Fig. 3.

Fig. 5 is an enlarged sectional view taken on line 5 of Fig. 3, and

Fig. 6 is a similar sectional view taken on 55 line 6 of Fig. 3.

Surface plates for the above purpose as now commonly used include a straight upper portion having a flat top surface, and are reinforced upon their underside with 60 ribs that extend both cross-wise and longitudinally. This form of rib reinforcement now has to be made heavy in order to give the required strength to the plates, but which makes the plates bulky to handle and 65 expensive to manufacture.

As will be noted, my present invention is designed so as to preferably be made of one piece of metal, and formed by casting the same in a suitable mold with the use of 70 cores of the required size properly placed so that a complete plate can be made with one pouring of metal and so as to require but a slight amount of work to finish the surface.

In the drawing, 10 represents the straight upper portion of the plate, having a top operating surface 11, which is reinforced and strengthened wholly upon the underside by suitable bridging and intermediate supporting posts, all of which may be made comparatively light and are specially arranged and shaped to give to the completed article the required amount of rigidity. The legs 12 upon which the plate is supported are 80 also formed integral with the body of the plate and their bottom ends are finished so as to be spaced equal distances from the operating surface of the plate.

The bridging 13 is in curved formation 90 and may include a single wall forming a curved bowl-like bridge, producing a single chamber in which are positioned a series of vertical posts 14 that extend from the inner wall of the bridging up to the underside of the top portion of the plate, in a way to strengthen the same, or it may include a series of such curved reinforcing bowl-like walls which intersect one with the other to form a series of compartments 15 and 16 that are also provided with posts to support and strengthen the structure. Upon the underside of the corners of the plate including the bowls are formed radially disposed ribs 18 as shown, which extend out under 100 the corners of the plate to properly support the same. The several compartments or spaces beneath the bridging are provided 105

with a series of core holes 17 whereby the cores for the casting may be removed and upon the ends of the plate are formed reinforced holes 19 for the attachment of handles, not shown.

Having thus described my invention, what I claim and desire to secure by Letters Patent, is—

1. A metal surface plate including a top portion having an operating surface, bridging concave-convex portions formed integral with the top body portion and inclosing pockets therewith, and posts in the pockets connecting the bridging to the body portion.
2. A metal surface plate including a top body portion having an operating surface, a bridging concave-convex portion formed

on the underside thereof, and web portions formed under the bridging and corners of the plate.

3. A metal surface plate including a top body portion having an operating surface, intersecting bridging concave-convex portions formed on the underside thereof, and additional means intermediate of the top and bridging for supporting the plate, and openings in the bridging.

Signed at Bridgeport, in the county of Fairfield and State of Connecticut, this 27th day of October, A. D. 1919.

FRANK O. HOAGLAND.
